ALOIS DANNINGER, HERBERT SCHMOLKA, AND RICHARD KASTNER, OF STEYRERMUHL,
AUSTRIA

METHOD AND APPARATUS FOR THE FREEING FROM WATER OF WEBS OF PAPER,
CELLULOSE, AND THE LIKE

Application filed September 4, 1928, Serial No. 303,758, and in Austria September 12, 1927.

As it is known, webs of paper, cellulose and the like are passed through wet-presses for leading off in a mechanical way as much as possible of the water contained in the web in order to be able to execute the subsequent drying in the usually steam-heated drying-cylinders with a lower rate of heat. The quantity of the water removed from the paper or cellulose web by means of the wet-
5 presses could be increased by this that the paper or cellulose web is heated within the wet-press-system, that is before the last wet-press, with the effect to reduce the viscosity of the water. However, this intermediate
10 heating in the wet-press-system cannot be carried out in the manner usual in paper-machines, that is to say by means of heated cylinders for the following reason: As well known in the art the webs of paper or cellulose have still a high water-content (80 to 90 per cent and more) before the last wet-press and for heating these relatively great quantities of water in a very short time to a temperature of 60° to 80° C. the heating cylinders
15 must have a high temperature. By the contact with the hot cylinders the webs of paper or cellulose which in consequence of their high water contents are still very liable to be affected would become defective and further-
20 more in some cases the gluing of the paper or cellulose web would be unfavourably influenced by the excessive heating of the outermost fibers which are in contact with the heating-cylinders.
25 According to the present invention the heating of the paper or cellulose web is brought about within the wet-press-system, that is to say before the last wet-press, by means of heating elements preferably act-
30 ing by radiation of heat and in a preferred form constructed as electric radiation heat-
35 ing elements, which are free from any direct contact with the web. In this way all detrimental actions on the paper or cellulose
40 web are prevented.

A further feature of the invention consists in the fact that the part of the web-paper or cellulose web itself, which is situated just in front of the wet-presses, serves as an elec-
45 tric resistance heating element. The current

passing through this part of the web heats the paper or cellulose web together with the water contained therein. For the intermediate heating of the paper or cellulose web within the wet-press-system superheated steam or hot air or a mixture of steam and hot air may also be used.
55

The invention also relates to the apparatus for carrying out the new method.

In the drawing which illustrates a con-
60 structional form of the apparatus according to the invention, the figure shows a view of a device for the intermediate heating of the paper or cellulose web by means of electric radiation heating elements.
65

In the form of construction shown in the figure the paper or cellulose web *a* which arrives in the usual manner from the wet-
70 system (sieve-system or the like, first wet-
presses) of the paper machine or the like and which has still a very high water content is carried over two rolls *b*, *c* before it comes to the last wet-press *d*, *f*. On the one side of the wet-paper or cellulose web *a* a series of electric radiation heating elements is pro-
75 vided which for example consists of resist-
ance wires *g* supplied by electric current. These resistance wires *g* extend preferably over the whole breadth of the paper or cel-
lulose web *a* and are arranged in reflectors *h* of parabolic cross-section which have the form of soffits, that means that the reflectors *h* extend also over the whole breadth of the web. On the other side of the paper or cel-
80 lulose web *a* a reflector *i* in the form of a screen is provided, which reflects the rays of heat passing for a part through the web *a*, so that the web *a* is radiated from both sides without the necessity of arranging the radi-
85 ation heating elements also on both sides.
90

The described apparatus enables a very intensive supply of heat to the wet paper or cellulose web *a*, so that the water content of this web is heated to a temperature of 60° to 80° C. notwithstanding the great speed of
95 the web (about 2 to 5m/sec) and notwithstanding the radiation taking place for some seconds or for fractions of seconds only. The paper or cellulose web becomes in this manner uniformly heated through its entire
100

thickness without any detrimental action on the web. By means of the intermediate heating the viscosity of the water contained in the web *a* is reduced so far that the following wet-press *d*, *f* is capable to press off a quantity of water which is much greater than it would be the case without the intermediate heating. The paper or cellulose web leaves the wet-press with a much higher degree of dryness, so that the amount of heat which must be supplied in the following drying-system of the paper-machine is considerably reduced.

In case of interruptions of the working, for example on breakage of the paper or cellulose web *a* this web would become completely dried under the action of the radiation heating elements *g* or the web could come in contact with the said heating elements *g*, with the risk that the web catches fire. For preventing this, screening devices are provided, which are situated in front of the reflectors *h* and which have in the illustrated example the form of flaps *j* which are connected for common operation by a lever system *m*. In case of interruptions of the working, for example on breakage of the web *a* the flaps *j* are closed by hand or by means of an automatic device. It will be understood that the arrangement may also be such that in case of interruptions of the working the radiation heating elements *g* themselves will be automatically switched off.

It is self-evident that the heating elements *g* may be heated also in another way than by means of electric current so as to bring about a sufficiently intensive radiation of the paper or cellulose web *a*.

The intermediate heating of the paper or cellulose web in the wet-press-system may be effected according to this invention also in such a manner that the wet-felt travelling together with the paper or cellulose web is heated simultaneously with this web or is heated alone. The wet-felt may be heated in the described manner by radiation, that means indirectly or it may be in contact with the heating cylinder whilst only the heating of the paper or cellulose web is effected indirectly. In this form of the method a partially drying of the wet-felt is obtained that will be advantageous for the working and for the life of the felt.

What we claim is:

1. An apparatus for removing superfluous water from webs of paper and cellulose, comprising a wet-press, a series of rolls for carrying the wet-web to said press, heating elements having highly effective radiation, said elements being uniformly spaced along one side of the path of the web and reflectors for each heating element adapted to carry the heat against the surface of the web, and another reflector on the opposite side of the web adapted to return heat waves

to the web having passed through the same from the first reflectors.

2. An apparatus for removing superfluous water from webs of paper and cellulose, comprising a wet-press, a series of rolls for carrying the wet web to said press, heating elements having highly effective radiation, said elements being uniformly spaced along one side of the path of the web and parabolic reflectors for each heating element adapted to carry the heat against the surface of the web, and a flat reflector on the opposite side of the web adapted to return heat waves to the web having passed through the same from the parabolic reflectors.

3. An apparatus for removing superfluous water from webs of paper and cellulose, comprising a wet-press, a series of rolls for carrying the wet-web to said press, heating elements having highly effective radiation, said elements being uniformly spaced along one side of the path of the web and parabolic reflectors for each heating element adapted to carry the heat against the surface of the web, and a flat reflector on the opposite side of the web adapted to return heat waves to the web having passed through the same from the parabolic reflectors, and flaps hinged to the edges of the parabolic reflectors and adapted to close in front of said heating elements in order to regulate the heat passing from the parabolic reflectors to said web.

4. A method of removing superfluous water from a wet-web consisting in carrying said web past highly effective heating elements at a speed of approximately 2 to 5 meters per second and exposing the web to heat of 60° to 80° C., and finally pressing the web between suitable rollers.

In testimony whereof we have affixed our signatures.
